UNITED STATES PATENT OFFICE.

STEPHEN TACTKIAN, OF NEW YORK, N. Y.

CAMERA.

1,269,021.

Specification of Letters Patent. Patented June 11, 1918.

Application filed June 23, 1916. Serial No. 105,397.

To all whom it may concern:

Be it known that I, STEPHEN TACTKIAN, a subject of the Kingdom of Great Britain, residing at New York, in the county and State of New York, have invented certain new and useful Improvements in Cameras, of which the following is a specification.

This invention has more particular reference to cameras of the type in which a continuous strip of sensitized material, commonly called a film strip or film roll, is adapted to receive the impressions for a plurality of pictures, the strip being advanced as desired, to bring successive portions thereof into juxtaposition with the lens. The invention relates to the film strip manipulating means, having no reference to the mechanism for making the photographic impression thereon.

Heretofore in cameras of this type, it has been necessary, if waste of a portion of the film strip is to be avoided, to wait until the full number of impressions have been made on the film strip, hereinafter generally referred to as the film, before it was possible to develop and print any individual picture, this being often inconvenient.

It is an object of this invention to provide a means whereby such portion or portions of the film as may have been exposed to receive the photographic impression, may be developed and printed, when desired, without any waste of the unexposed portions of the film.

A further object is to provide a means whereby the exposed portion of the film may be separated from the unexposed portion and removed, and the unexposed portion advanced again as desired into relation with the lens. Another object is to provide a device of this kind which will be capable of easy application to existing types of cameras. Another object is to provide a device of this kind which will be of simple construction and easy operation.

For further comprehension of the invention, and of the objects and advantages thereof, reference will be had to the following description, taken in conjunction with the accompanying drawings, and to the appended claims in which the various novel features of the invention are more particularly set forth.

In the accompanying drawings which serve to illustrate my invention, Figure 1 is a side elevation, partly in transverse section,

of a camera having the invention applied thereto. Fig. 2 is a rear view of one end of the camera, portions of the casing being broken away to show the interior parts. Fig. 3 is a substantially horizontal section, being 60 taken on the line III—III of Fig. 1. Fig. 4 is a vertical section roughly on the line IV—IV of Fig. 3, the film severing device being shown in elevation. Fig. 5 is a vertical section similar to Fig. 3, but enlarged 65 and showing both the film severing device and winding spool in longitudinal section. Figs. 6 and 7 are transverse sections both on the line VI—VI of Fig. 5, showing different stages of the operation of securing 70 the unused portion of the film to the winding spool. Fig. 8 is a side view of the winding spool, part of the spool being broken out to show the film gripping teeth. Fig. 9 is an end elevation of that portion of the camera 75 illustrated in the preceding views. Figs. 10 and 11 are views similar to Figs. 6 and 7, but showing different operative positions of various parts. Fig. 12 is a detail section illustrating particularly the displaceable support for the spool trunnions. Fig. 13 is a perspective view of the detachable spool casing carrying the film severing knives. Fig. 14 is a transverse sectional view, and Fig. 15 a longitudinal sectional view, of a modified form of winding spool.

In the following description, the portion of the film which has been exposed to receive the photographic impression is referred to generally as the exposed portion 90 of the film, the remainder being called the unexposed portion. To facilitate understanding the following description, the embodiment of the invention here shown may be said to be divided into three general parts 95 or devices, which may be enumerated briefly as follows: A means for gripping and holding in proper position, the severed end of the unexposed portion of the film; a means for severing the exposed portion of the film 100 from the unexposed portion of the film; a means whereby the unexposed portion of the film may be again operatively engaged by the film advancing device.

As here illustrated, I have embodied my 105 invention in, or applied it to, a camera of ordinary construction, the casing whereof is indicated generally by the reference numeral 1, this camera having at opposite ends, the usual spool chambers 2 and 3, in the former 110

of which the roll of unexposed film is mounted in the usual manner, while my invention is in the form of a compact, detachable device mounted in the opposite spool chamber 3.

Screwed into a threaded opening in one of the end walls 5 of the spool chamber 3, is a head 6 which may have a milled flange 7 to permit of easy rotation. This 10 head forms one end of the device for holding in proper position the severed end of the film, the opposite end of such device being in the form of a flanged disk or head 8, supported in the other wall 5 of the spool chamber 3. These heads 6 and 8 are connected by a cylinder made up of two longitudinally divided halves 9 and 10, arranged to have relative movement toward and away from one another to constitute the 15 film engaging jaws. As here shown the part 10 is fixed to the heads 6 and 8, while the part 9 constitutes a clamping jaw and is fixed upon a hinge pintle 11 rotatably supported at opposite ends in the heads 6 and 20 8, such pintle being rotatable to swing the part 9 by suitable means as the yoke shaped handle 12 hinged upon the projecting end of the pintle and adapted to engage a pin 13 to hold the part 9 in either open or 25 closed position, as desired. As will be seen the hinge 11 is so disposed that the jaws open toward the rear of the chamber 3, into which the film, indicated by the numeral 15, is introduced in a well known manner 30 through the slot 16 and over the roller 17. Normally these jaws are open to permit of the film passing freely therethrough, to wind upon the receiving spool.

Carried within this cylinder is the film 40 severing means which, as here shown, comprises a pair of coöperating knives 25 and 26, formed on the edges of a pair of semi-cylindrical members 27 and 28, the knife 25 being a stationary knife and the knife 45 26 being movable, the semi-cylindrical member 27 being here shown as fixed upon a hinge pintle 29 located adjacent the pintle 11 and rotatably supported at its opposite ends in a pair of heads 30 and 31, the first 50 of which is screwed into a threaded opening in the head 6, the other being freely supported by the flanged disk 8. Upon the projecting end of this pintle 29 is a yoke shaped handle 32 similar to the handle 12, and coöperating in similar manner with a pin 33 on the head 30 to hold the knife 26 55 in engagement with or removed from the knife 25. It will be noted that the members 27 and 28, together with the heads 30 and 31, constitute a detachable casing closed 60 when the knives 25 and 26 are in engagement with one another. The semi-cylindrical member 28 is in the present instance, formed of resilient metal and is fixed to the 65 heads 30 and 31 at the opposite edge to that

carrying the knife 25, the edge carrying such knife being free. The purpose of this arrangement will be pointed out later.

Referring now to the means by which the film is advanced, the winding spool is 70 mounted concentrically within the cylindrical gripping and cutting devices just described being supported at its ends in the heads 30 and 31. This winding spool is split longitudinally into a pair of gripping jaws 75 35 and 36, hinged at the circumference of the spool upon a rod 37, supported by the spool ends 38, and which are shown as normally pressed together by the spring 39 and provided with the pins or teeth 40. 80 The spool ends 38 have fixed thereto trunnions 41, by which the spool is supported in the heads 30 and 31. These trunnions are hollow and rotatably support a rod 42 which passes axially through the spool between the jaws 35 and 36, and is provided with cam members 43 which, when the rod is rotated in a direction opposite to that in which the spool is rotated to wind the film thereon, engage suitable coacting surfaces 85 44 on the interior of the jaws to force the latter apart so as to permit insertion or withdrawal of the film. The rod 42 may be rotated by means of a handle 42' similar to the handles 12 and 32 on the end thereof. 90 Any suitable means may be provided by which the spool is caused to rotate with the rod, instead of the latter separating the jaws, when the rod is rotated in an opposite or winding direction. As here shown one of the cams 43 engages with the hinge member of one of the jaws, as indicated in Fig. 7. In the normal winding position of the spool, backward rotation or rotation in an unwinding direction of the rod, is prevented 105 by any suitable means, such as the pawl 45 on the head 30 engaging a ratchet wheel 46 on the rod 42, it being thus impossible to either unwind the film from the spool, or to open the spool jaws, when the spool is in 110 normal position.

In order to enable the unexposed portion of the film remaining in the camera, to be again secured to the spool after the exposed portion has been severed therefrom by the 115 knives 25 and 26, as will be pointed out more fully later, I provide a means for again operatively connecting the portion of the film remaining in the camera to the winding spool. In the present embodiment of my invention, the spool is adapted to be moved bodily toward the holding members 9 and 10 and grip the edge portion 15' of the film which projects inwardly from the positioning jaws after the film has been severed. 120 To this end the spool trunnions bear in slots 50 in the heads 30 and 31, such slots extending rearwardly in a line intersecting the meeting line of the positioning jaws. These 125 slots each have a portion thereof narrowed 130

as at 51 to receive flattened portions 52 on the spool trunnions, the engagement of such narrow slots and flat trunnions preventing rotation of the spool when it is moved toward the holding jaws. Suitable means are provided for normally retaining the spool in proper winding position at the forward ends of the slots 50. As here shown a pair of springs 53 (Fig. 12) having curved ends fitting the rounded portions of the trunnions are located at opposite sides of each of the slots 50, these springs being of sufficient strength to resist any pull on spool due to the winding of the film thereon, but not of sufficient strength to prevent the trunnions being pushed into the slots 50. If desired, these springs may be made double ended as shown, to engage the spool trunnions at both ends of the slots. Suitable means are preferably provided whereby when one end of the spool is moved, the other end thereof will be caused to move in unison therewith. I have here shown a pair of bell crank levers 54 and 55 mounted in slots 56 and 57 in the heads 30 and 31, and in operative connection by the rod or link 58 connected to one arm of each. The opposite arm of each bell crank lever is connected to the trunnions 41 by links 59 and 60 loosely encircling the latter. To prevent access of light to the interior of the detachable casing comprising the parts 27, 28, 30 and 31, a plate 61 may be loosely mounted on the end of the spool trunnion, which projects through the head 30, adjacent such plate and in position to cover the slot 50, being suitably guided, as by the slots 62 therein engaging pins 63 on the head 30. The outer face of the trunnion slot in the head 31 may be permanently closed, as indicated at 64. To accommodate movement of the spool in the slots, the spool ends 38 may be cut away as shown at 65.

In Figs. 14 and 15 I have shown a modified form of spool provided with means whereby the jaws 35 and 36 may be positively forced together. In this case the rod 42 is separated into a pair of rods 65 and 66, which are disposed in cam slots 67 and 68 in the jaws. Rotation of the rod 42 in one direction will separate the jaws while upon movement in the opposite direction, the rods 65 and 66 will engage the inner surfaces of the cam slots 67 and 68 and so assist the spring 39 in forcing the teeth 40 through the end of the film.

The manner of operation is as follows: The film strip is inserted in the camera in the usual manner, being rotatably mounted in the spool chamber 2, and the end thereof brought up into the chamber 3. The handles 12 and 32 having been rotated to provide an opening between the holding jaws and between the severing knives, the winding spool is rotated by handle 42' in a wind-

ing direction until the flattened trunnion portions 52 are in alignment with the narrowed slot portions 51. The spool is then moved rearwardly in the slots, the springs 53 yielding. When the spool has been moved into the slots, the ratchet wheel 46 disengages from the pawl 45, thus permitting rotation of the handle 42' in a backward direction, while the spool as a whole, is prevented from rotation by the engagement of the flattened trunnion portions 52 with the sides of the narrowed portions 51 of the slots 50. The handle 42' is now rotated to cause the cams 43 to separate the jaws 35 and 36. The end of the film may then be introduced by hand between the jaws and the handle 42' rotated to allow the spring 39 to close the jaws upon the film. The spool is then moved back to its winding position and the film may be wound thereon as portions thereof are successively exposed, in the usual manner. If it is desired to develop any exposed portion of the film before the entire film has been exposed, the handle 12 is rotated to close the member 9 down upon the member 10, the film being gripped as shown between such members. The handle 32 is then rotated to cause the knife 26 to close upon the knife 25 and sever the portion of the film upon the spool from the remainder. By unscrewing the head 30 from the head 6, the spool with its inclosing casing, made up of parts 27, 28, 30, 31, may be removed from the camera without exposure of the film to the light. The head 30 may be provided with suitable projections to facilitate rotation, or the handles 32 and 42' may be used as a means to grasp the head. The spool and casing may again be inserted in the camera after removal of the film therefrom, or a second spool and casing may be provided to be immediately inserted in place. To do this, the head 30 is screwed again into the head 6, the knives 25 and 26 are separated, and the spool is moved into the slots 50 as above described, and jaws 35 and 36 thereof are opened. The spool is then pushed rearwardly to the end of the slots, in which position the jaws extend over the end portion 15' of the film, which projects inwardly from the gripping members 9 and 10. It will be noted that the resilient member 28 yields, as indicated in Fig. 6, as the spool is moved to the rear end of the slot, to permit of sufficient movement of the spool to bring the jaws thereof into engaging relation with the end of the film. If desired, this result may be accomplished by other means, such for instance, as making both parts 27 and 28 movable in unison. The spool jaws are again closed and the spool returned to the forward end of the slot, drawing the film with it. The gripping member 9 is then released and the film strip may again be wound in the usual manner

on the spool. This operation may be repeated as often as it is desired to remove and develop a portion of the film strip.

It will be apparent that many changes and modifications might be made in the device as here shown, without departing from the principle of my invention, the above description and accompanying drawings serving to illustrate such principle.

10 Having thus described my invention, I claim:

1. In a camera, the combination with means for supporting a film strip, of means forming a part of the camera, whereby a portion of the strip may be separated from the remainder, and means also forming a part of the camera and removable therefrom, whereby the separated portion may be removed from the camera without being exposed to light.

2. In a camera adapted to support and advance a film strip, a closed casing detachably mounted on the camera adapted to receive the exposed portions of the film strip, and means for separating the portion of the strip in the said casing from the remainder, such means comprising a cutting device mounted in the said camera adjacent the said casing.

3. In a camera, in combination with film strip supporting means, means for severing a portion of the film strip from the remainder, a winding spool provided with film gripping means adapted to move bodily into juxtaposition with the end portion of the said remainder, and means holding the said end of the film strip in position to be engaged by the said film strip gripping means.

4. In a camera adapted to hold and advance a film strip, a closed casing detachably mounted on the camera adapted to receive the exposed portion of the film strip, said casing having a member adapted to be moved to provide an opening for the passage of the strip, the said member carrying a cutting part whereby when the member is moved to close the casing, the portion of the film strip within the casing will be severed from the remainder.

5. In a camera adapted to support and advance a film strip, a closed casing detachably mounted on the camera, a spool carried by said casing on which the said strip is adapted to be wound, said casing having a member adapted to be moved to provide an opening for the passage of the strip, a cutting device mounted on said member adapted to sever the portion of the film strip wound upon the said spool from the remainder when the said member is moved to close the casing, means holding the end of said remainder in juxtaposition with the line of opening of said casing, and means whereby the said spool may be moved bodily toward the said line of opening to engage the said strip end.

6. In a camera, a film strip winding spool having a pair of relatively movable film gripping jaws operable from the exterior of the camera casing.

7. In a camera, a film strip severing device, a film strip winding spool having a pair of relatively movable film gripping jaws operable from the exterior of the camera, and means whereby the said spool may be moved bodily to bring the jaws thereof into juxtaposition with the severed end of the film strip.

8. In a camera, a film strip severing device, a film strip winding spool having a pair of relatively movable film strip gripping jaws operable from the exterior of the camera, means holding the severed end of the film strip against displacement, and means whereby the spool may be moved bodily to bring the jaws thereof into juxtaposition with the severed end of the film strip.

9. In a camera, a film strip winding spool having a pair of relatively movable film strip gripping jaws, means for operating such jaws, and means preventing operation of said jaws when the spool is in normal winding position.

10. In a camera, a film strip winding spool having a pair of relatively movable film strip gripping jaws, a common handle for opening said jaws and rotating the spool, and means for preventing operation of the handle to open the jaws when the spool is in normal winding position.

11. In a camera, a bodily movable film strip winding spool having a pair of relatively movable film strip gripping jaws, a common handle for operating said jaws and rotating the spool, means for preventing operation of the jaws when the spool is in normal winding position, and means adapted to permit operation of the jaws and to prevent rotation of the spool when the latter is displaced from normal winding position.

12. In a camera, a winding spool having a pair of relatively movable film strip gripping jaws, a common means for operating the jaws and rotating the spool, and means for preventing operation of the jaws when the spool is in normal winding position.

13. In a camera, a bodily movable film strip winding spool having a pair of relatively movable film strip gripping jaws, a common handle for operating said jaws and rotating the spool, means for preventing operation of the jaws by said handle when the spool is in normal winding position, and means adapted to permit operation of the jaws but prevent rotation of the spool when the latter is displaced from normal winding position.

14. In a camera adapted to support a film strip, a casing disposed therein having

an opening for the passage of the film strip, provided on its edges with film strip gripping means, a second casing within the first having an opening for the passage of the film strip provided on its edges with film strip severing means, and a winding spool within said second casing having film strip gripping means.

15. In a camera adapted to support a film strip, a casing disposed therein having an opening for the passage of the film strip, provided on its edges with a film strip gripping means, a second casing within the first having an opening for the passage of the film strip provided on its edges with film strip severing means, a winding spool within said second casing having film strip gripping means, said winding spool being bodily movable toward the said opening in the second casing.

16. In a camera adapted to support a film strip, a casing disposed therein having an opening for the passage of the film strip, provided on its edges with a film strip gripping means, a second casing within the first having an opening for the passage of the film strip provided on its edges with film strip severing means, a winding spool within said second casing having film strip gripping means, said winding spool being bodily movable toward the said opening in the second casing, and means whereby both

ends of said spool may be caused to move in unison toward the said opening.

17. In a camera adapted to support a film strip, a casing disposed therein having an opening for the passage of the film strip, provided on its edges with a film strip gripping means, a second casing within the first having an opening for the passage of the film strip provided on its edges with film strip severing means, a winding spool within said second casing having film strip gripping means, said winding spool being bodily movable toward the said opening in the second casing, and displaceable means adapted to retain said spool in normal winding position.

18. In a camera adapted to support and advance a film strip, a receptacle closed so as to exclude light detachably mounted on the camera and adapted to receive the exposed portion of the film strip, means mounted within said receptacle for gripping and winding said film within the receptacle, and a part of said receptacle comprising means for severing the portion of the strip in the said receptacle from the remainder.

In testimony whereof, I affix my signature, in the presence of two witnesses.

STEPHEN TACTKIAN.
